UNITED STATES PATENT OFFICE.

CHARLES POUZAR, OF CHICAGO, ILLINOIS.

ADJUSTABLE FORM FOR WRAPPING MACHINES.

Application filed July 18, 1924. Serial No. 726,717.

This invention relates to improvements in adjustable forms used in connection with wrapping machines and has particular reference to an adjustable form used for supporting paper boxes during the operation of applying the wrapper or label on same.

An object of the invention is to provide a form of the above stated character which shall be readily adjustable as to length and 10 width for accommodation of various sizes of boxes.

Another object of this invention is the provision of a steel adjustable form which can be readily attached to the spur of the top 15 plunger of a wrapping machine and which is adapted to permit the passage of strippers through same for automatically releasing the box from the form after the application of the label or wrapper.

20 A still further object of my invention embodies a novel construction of the form wherein the retaining screws of the form are relieved of any pressure which is applied to the form during operation; such pressure 25 being taken or resisted by the shoulders provided on the separate form members.

With these and other objects in view, my invention consists in the novel combination and construction of the various parts and 30 members illustrated in a preferred embodiment in the accompanying drawings, described in the following specifications and particularly pointed out in the appended claims.

35 Referring to the drawings, in which like reference characters indicate like or corresponding parts or members, Fig. 1, is a plan view of one of my forms, and Fig. 2, a side elevation of same.

40 Fig. 3 is also a plan view of my form for a box of different dimensions to that shown in Fig. 1, and Fig. 4 is a longitudinal section taken on line 4—4 of Fig. 3.

Fig. 5 shows a part of a wrapping machine 45 which one assembly of my form in longitudinal section, and Fig. 6 is a plan view of the form taken on line 6—6 of Fig. 5.

Fig. 7, is an illustration in perspective view of the form shown in Figs. 5 and 6, 50 with the various members in separated or spaced relation showing the details of construction.

Figs. 8, 9 and 10, are diagrammatic illustrations showing respectively three steps in 55 the operation of a wrapping machine employing my novel form.

Referring now particularly to Figs. 5, 6 and 7, the top reciprocating plunger 20 of a wrapping machine is adapted to retain by means of screw 21, a spur 22, the lower 60 end of which is flanged as at 22^A and provided with screws 23 for secure retention of a plate 24 commonly termed, the middle form.

A plate 25 is supported on the threaded 65 lower ends of the two rods 26 which extend through the bushings 27 within the enlarged head of the plunger 20 to a mechanism (not shown) in the upper part of the wrapping machine which reciprocates the rods 26 independently of the plunger 20 and the middle form plate 24 which is attached to the spur 22.

My improved form is generally indicated by numeral 28 and comprises the corner 75 members 29, side intermediate members 30 and end intermediate members 31.

Each corner member 29 is provided with slots in their ends which are right-angularly disposed to each other and adapted to receive the ends of the intermediate members. The intermediate members 30 are formed with shoulders 30^A which abut with the ends of the corner members 29, and, in forms using plain intermediate members such as 80 31, the corner members 29 are brought in contact with each other, the design of my improved form being such that the screws 32, which securely hold the form together, are relieved of any pressure during the 85 operation of the rollers against the form in the application of the labels or wrappers to the box.

The corner members 29 are further provided with vertical passages 29^A which are 90 in alignment with the holes 24^A of the plate 24 to permit the passage of the stripping rods 33 of the wrapping machine. The purpose of the stripping rods is to remove the box from the form 28 after the application 95 of the wrapper or label and they are also independently operated by suitable mechanism of the wrapping machine not here shown as such mechanism is not a part of my invention. 100

The form 28 as shown in Figs. 5, 6 and 7 is secured to a form supporting plate 34 by means of screws 35 which engage within the threaded holes 29^B of the corner members 29. The form supporting plate 34 is securely attached to the plate 25 by cap screws 110 25^A within the slots 25^B. 105

In a form having long side intermediate members 30, such as shown in Figs. 1 and 2, the members 30 are made with integral lugs 30^B having threaded holes adapted to receive the screws 35 of the form supporting plate 34.

In forms having comparatively long side and end intermediate members such as is shown in Figs. 3 and 4, I provide a special 10 form supporting plate 36 having longitudinally elongated slots 36^A for the cap screws 37 which secure same by engagement into one of the plurality of threaded holes 38^A in the brackets 38. The brackets 38 have 15 a downwardly disposed flange 38^B which is threaded for cap screw 39 within the end intermediate member 40. A pin 38^C integral with the flange 38^B extends within the end intermediate member 40 to more rigidly 20 support the bracket 38.

Figs. 8, 9 and 10, show diagrammatically, three steps in the operation of a wrapping machine employing my form. In Fig. 8, the paper box 41 which has been inserted on my 25 improved form is just passing through a pair of end pressure rolls 42 and the glued label 43 with upstanding ends has been glued to the ends of the box 41.

In the next step shown in Fig. 9, the form

28 has been lifted independently from the plate 24 to permit the inward movement of the fingers 44 which bend the upstanding ends of the glued label inwardly, whereby the downward return of the form 28 will securely glue label ends on the inner faces 30 of box ends, whereupon the stripping rods 33 are independently moved downwardly through the aligned openings 29^A and 24^A to strip the labeled box 41 from the form as clearly shown in Fig. 10.

I claim:

In an adjustable form for box wrapping machines, the combination of corner members, side intermediate members, end intermediate members, and means securing said side and end members with said corner members, the outer faces of said side and end intermediate members being flush with the outer faces of said corner members, said corner members having recesses in opposite 50 ends thereof, said side and end intermediate members being interfitting in said recesses with said corner members and in abutment therewith whereby the pressure on the sides of the form will be bodily resisted to relieve the said securing means.

In witness whereof I affix my signature.
CHARLES POUZAR.
